UNITED STATES PATENT OFFICE

OWEN S. LANTZ, OF SOUTH ESSEX, MASSACHUSETTS

RUDDER MOUNTING

Application filed August 15, 1932. Serial No. 628,931.

This invention relates to an assembly of parts which may be broadly referred to as a rudder mounting, and it has more specific reference to a special type bearing designed to effectively accommodate the oscillatory shaft carrying the rudder fin or blade. 5

The purpose of the invention is to provide a new and improved rudder mounting susceptible of meeting the requirements of a 10 special assemblage of this class, said mounting being desirable in that it is characterized by simplicity, ease and smoothness of operation, dependability and such additional noteworthy features as ruggedness, and durability. 15

Other features and advantages of the invention will become more readily apparent from the following description and drawing.

In the accompanying drawing wherein like 20 numerals are employed to designate like parts throughout the same:

Figure 1 is a side view, partly in section, showing a structure as developed in accordance with the fundamental ideas and principles of the invention. 25

Figure 2 is a fragmentary view in section and elevation, on an enlarged scale, showing the essential features.

Figure 3 is a horizontal section on the line 30 3—3 of Figure 1.

Figure 4 is a detail elevational view of the clamp equipped sleeve.

Referring now to the illustrated drawing and to Figure 1 it will be observed that the 35 numeral 5 designates the deck of the boat which is formed in its rear end with a vertical bore 6 directly below which is a socketed extension 7 carried by the rear terminal of the keel 8. The socket in the extension 7 serves to accommodate a trunnion 9 on the lower end of a perpendicular oscillatory shaft 10 which extends upwardly through and beyond the bore 6. On the upper end of the shaft 40 45 is the usual operating crank 11.

As shown in Figure 2 and in accordance with the principles of this invention a bushing 12 is fitted into the upper end portion of the bore 6 said bushing being provided at 50 its top with a disk-like attaching flange 13

riveted or otherwise secured to the deck of the boat.

The numeral 14 designates a two-part or split wear sleeve whose upper end portion is enlarged to form a clamping collar 15, said collar being located above the integral intermediate flange 16. Carried by this collar and located on opposite sides of the slot are complementary flanges 17 to accommodate the clamping and retaining bolts 18. The sleeve 14 is dropped down into the bushing and the flange 16 is seated on the plate or disk 13 and the collar 15 is clamped tightly around the upper protruding end portion of the shaft 10. The numeral 19 designates a retention clip bolted to the plate 13 and having a laterally offset retaining finger 20 which fits over the flange 16, thereby maintaining the parts in proper relationship and at the same time permitting the requisite oscillatory motion of the shaft and the rudder 21 carried by the lower portion of the shaft as shown in Figure 1. 60 65 70

The essential features of the invention are, first, the bushing 12 fitted in the upper 75 portion of the bore 6 and carrying an attaching plate 13 is a predominating factor. Secondly, the two-part sleeve unit shown in Figure 4 and comprising the sleeve 14, the shouldered clamping collar 15 and the retaining flange 16 is important. This serves as a wear member and the sleeve portion thereof depends into the bushing 12. Then, too, the clip 19 with its laterally offset retaining finger 20 is a distinguishing element. 80 85 Collectively considered, these parts form a novel and efficient assembly providing an effective bearing and mounting for the oscillatory shaft of the rudder structure. The structure thus constructed is smooth and 90 effective in operation, is susceptible of proper lubrication and maintenance, and otherwise capable of fulfilling the requirements of the invention in gratifying and satisfactory manner. 95

It is thought that persons skilled in the art to which the invention relates will be able to obtain a clear understanding of the invention after considering the description in connection with the drawing. Therefore, 100

a more lengthy description is regarded as unnecessary.

Minor changes in shape, size, and rearrangement of details coming within the field of invention claimed may be resorted to in actual practice, if desired.

I claim:

As a new article of manufacture, a rudder mounting comprising a bushing formed with a disk-like attaching plate, a sleeve adapted to fit telescopically in the bushing and designed to surround the rudder shaft, said sleeve having its upper end longitudi-

nally slit and formed with radial, longitudinally extending clamping flanges, said upper end constituting a clamping collar, the intermediate portion of the sleeve being formed with an outstanding circumferential flange adapted to rest on said plate, and a clip secured to said plate and having one end portion positioned to engage over said circumferential flange, and to also engage said clamping flanges for limiting oscillatory movement of the rudder shaft.

In testimony whereof I affix my signature.

OWEN S. LANTZ.
